UNITED STATES PATENT OFFICE.

LOUIS H. MCKEE, OF TRENTON, NEW JERSEY.

DESIGN FOR A SCHOOL-DESK.

48,076.

Specification for Design.

Patented Nov. 2, 1915.

Application filed January 23, 1915. Serial No. 4,059. Term of patent 14 years.

To all whom it may concern:

Be it known that I, LOUIS H. MCKEE, a citizen of the United States, residing at Trenton, in the county of Mercer, State of New Jersey, have invented a new, original, and ornamental Design for School-Desks, of which the following is a specification, reference being had to the accompanying drawing, forming part thereof.

Copies of this patent may be obtained for five cents each, by addressing the "Commissioner of Patents, Washington, D. C."

The figure is a side elevation of a school desk showing my new design.

I claim:

The ornamental design for a school desk substantially as shown.

LOUIS H. MCKEE.
